UNITED STATES PATENT OFFICE

MAURICE HAUPT, OF MONTREAL, QUEBEC, CANADA

DESIGN FOR A BOTTLE

Application filed March 18, 1930. Serial No. 34,954. Term of patent 14 years.

To all whom it may concern:

Be it known that I, MAURICE HAUPT, a Canadian citizen, residing at Montreal, in the Province of Quebec, Dominion of Canada, have invented a new, original, and ornamental Design for Bottles, of which the following is a specification, reference being had to the accompanying drawing, forming part thereof.

I claim:

The ornamental design for a bottle, as shown.

MAURICE HAUPT.
